UNITED STATES PATENT OFFICE

EROS V. BARKER, OF BELLEVUE, OHIO, ASSIGNOR TO JACOB F. MARTIN, OF BELLEVUE, OHIO

DESIGN FOR A LUGGAGE CARRIER.

Application filed August 25, 1930. Serial No. 36,755. Term of patent 7 years.

To all whom it may concern:

Be it known that I, EROS V. BARKER, a citizen of the United States of America, residing at Bellevue, Sandusky County, Ohio, have invented a new, original, and ornamental Design for Luggage Carriers, of which the following is a specification, reference being had to the accompanying drawings, forming a part thereof.

Fig. 1 is a front elevational view of a luggage carrier, showing my design;

Fig. 2 is a view on the line II—II, Fig. 1; and

Fig. 3 is a view on the line III—III, Fig. 2.

I claim:

The ornamental design for a luggage carrier as shown.

EROS V. BARKER.
